CHILD'S PEG BOARD CLOTHES HANGER

Gordon A. Price, Canton, Ohio

Application July 3, 1951, Serial No. 15,752

Term of patent 7 years

(Cl. D33—8)

To all whom it may concern:

Be it known that I, Gordon A. Price, a citizen of the United States, residing at Canton, in the county of Stark and State of Ohio, have invented a new, original, and ornamental Design for a Child's Peg Board Clothes Hanger, of which the following is a specification, reference being had to the accompanying drawing, forming part hereof, in which:

I claim:

The ornamental design for a child's peg board clothes hanger, substantially as shown.

GORDON A. PRICE.
